CLAIM

The ornamental design for a receiver for an input device, as shown and described.

DESCRIPTION

FIG. 1 is a perspective view of a receiver for an input device showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line representation of the circular legs and the rectangular switch in FIG. 7 and the cord in FIGS. 1-3, 6 and 7 is for environmental purposes only and forms no part of the claimed design.
